UNITED STATES PATENT OFFICE.

DANIEL MEEHAN, OF NEW BEDFORD, MASSACHUSETTS.

DEVICE FOR GRINDING AND CLEARING DRILLS.

SPECIFICATION forming part of Letters Patent No. 282,209, dated July 31, 1883.

Application filed June 4, 1883. (Model.)

To all whom it may concern:

Be it known that I, DANIEL MEEHAN, a citizen of the United States, residing at New Bedford, in the county of Bristol and State of Massachusetts, have invented certain new and useful Improvements in Devices for Holding, Grinding, and Clearing Drills, of which the following is a specification, reference being had therein to the accompanying drawings.

10 This invention relates to grinding, clearing, and polishing drills, more particularly twist-drills; and it consists of an improved apparatus for holding a drill to an emery or grinding wheel when being ground or cleared, as 15 hereinafter fully described and shown.

In the accompanying drawings, Figure 1 is a perspective view of a drill-holder having my improvements. Fig. 2 is a side elevation. Fig. 3 is a top view. Fig. 4 is a rear view. Fig. 5 is a section of bearings or drill-holding plate and sliding plate. Fig. 6 is a partial view, showing drill and bearings in section, and illustrating the drill-clearing operation.

A designates the main stock supporting the 25 apparatus. B indicates a bed having a standard, *a*, projecting downward and sliding in a groove with which the stock A is provided. The standard carrying the bed B is raised or lowered, as desired, by means of a vertical 30 screw, *b*. The bed B is formed with a dovetail groove, in which slides a plate, *c*, which carries the bearings *d* of the drill to be ground or cleared. The bearings are formed with an 35 opening, *f*, to receive an emery or grinding wheel, as indicated at *x* in Figs. 2 and 3. A bent tongue or hooked spring, *g*, is secured in position, as shown, to be pressed down against the drill, which is passed through the bearings, as indicated at *z*, and when the drill is 40 drawn the spring-tongue enters the spiral groove and causes the drill to rotate, the grinding or clearing being effected at the same time by the emery-wheel. The term "clearing" is understood to mean the grinding away of the 45 drill in such a manner as to leave the spiral bearing-edge a little more prominent than the other portions, so that in using the drill there is no binding of it.

In Fig. 6 a drill is shown in section in the 50 bearings, the bearing-edge of the drill being marked *v*, and the grinding-wheel being indi-

cated by broken line *x*. It will be seen that the drill and the grinding-wheel are in such relative positions that the grinding-wheel bears against the drill at a point back from the edge *v*, this arrangement being effected by the vertical and horizontal adjustment of the bearings *d*, the spring *g* being pressed down so that its point enters the spiral groove of the drill, as shown, and the drill being drawn 60 through the bearings as the grinding-wheel revolves, the same relative positions of drill and wheel are preserved, and the surface ground forms a spiral track back of the edge *v* and parallel with said edge, a longitudinal 65 clearing of the drill being thus effected. The purpose of such clearing is to prevent the binding of the drill, when in use, by leaving the bearing-edge slightly more prominent than the surface back of it. The bearings *d* are 70 provided with a screw, *h*, which is located at any suitable point along the bearings, so that it may be made to bear against the drill from a direction opposite, or nearly so, to the bearing-point of the tongue *g*, the latter usually 75 bearing on the drill from above and the screw *h* from below, as seen in the drawings.

In operation the screw *h* enters the spiral groove of the drill, and serves as an additional guide in causing a steady rotation of the drill 80 as it is drawn through the bearings, thus co-operating for the purpose with the tongue *g*. The said screw also answers the purpose of an adjusting-screw when the bearings are rather larger than required for the drill to be ground, 85 the adjustment being effected by driving the screw farther inward against the drill, and thus practically reducing the space occupied by it. The operator, having placed the drill in the bearings *d*, can with one hand press 90 down the tongue *g* against the drill, the free end of the tongue entering the spiral groove of the drill. The drill being then drawn, the tongue causes it to rotate as it moves through the bearings, the screw *h* co-operating to cause 95 a steady rotation of the drill and keep it in contact with the grinding-wheel. A grinding-gage, *i*, is secured to the sliding plate *c* by means of a screw, *s*, the said gage being thus adjustable on plate *c*, which, when moved forward, is stopped by the gage *i* closing against the bed B.

The bearings *d*, being detachably secured to the plate *c*, may be readily removed, and new bearings or bearings of a different size may be substituted, as desired.

5 I claim—

1. A drill-holder for grinding and clearing purposes, having bearings for drills, and provided with a spring or tongue constructed to be pressed into the groove of the drill and 10 cause it to rotate as the drill is drawn through the bearings, substantially as and for the purpose set forth.

2. A drill-holding device for grinding and clearing purposes, provided with bearings *d*, 15 in combination with a tongue, *g*, and a screw,

h, the parts being constructed substantially as shown, for the purposes specified.

3. A drill-holder having adjustable bearings *d*, with an opening to receive a grinding-wheel, an adjusting-screw, *h*, a spring, *g*, and 20 gage *i*, in combination with the main stock provided with an adjusting-screw, *b*, substantially as set forth.

In testimony whereof I affix my signature in presence of two witnesses.

DANIEL MEEHAN.
